(57) **CLAIM**

The ornamental design for an automatic chicken coop door, as shown and described.

DESCRIPTION

FIG. 1 is a front, top and left perspective view of an automatic chicken coop door, showing my new design; FIG. 2 is a rear, right and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 3 thereof; and, FIG. 10 is a front perspective view shown in an open state thereof.

The broken lines shown in the drawings illustrate portions of the automatic chicken coop door that form no part of the claimed design.

The dot-dash-dot broken lines represent that boundaries of the detail enlargement that form no part of the claimed design.
